[57] CLAIM

The ornamental design for a adjustable support for a cellular telephone or the like, as shown and described.

DESCRIPTION

FIG. 1 is a front elevational view of an adjustable support for a cellular telephone or the like showing my new design, the rear being a mirror image thereof;
FIG. 2 is a right side elevational view thereof;
FIG. 3 is a left side elevational view thereof;
FIG. 4 is a top plan view thereof; and
FIG. 5 is a bottom plan view thereof.

Fig. 1.

Fig. 2.

Fig. 3.

Fig. 4.

Fig. 5.
